UNITED STATES PATENT OFFICE.

ISIDOR POMERANTZ, OF KANSAS CITY, MISSOURI, ASSIGNOR TO PHILIP S. DELANY,
OF KANSAS CITY, MISSOURI.

VENTILATOR.

1,116,625.

Specification of Letters Patent. Patented Nov. 10, 1914.

Application filed July 8, 1912. Serial No. 708,186.

To all whom it may concern:

Be it known that I, ISIDOR POMERANTZ, a citizen of the United States, residing at Kansas City, in the county of Jackson and State of Missouri, have invented certain new and useful Improvements in Ventilators; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to window ventilators, and has for its principal object to provide a ventilator which may be located entirely within a window sash, and is adapted for quick removal and return to the sash to facilitate cleaning.

It is also an object of the invention to provide a ventilator having means for screening or filtering the incoming air, and means for adjusting the ventilating area of the device.

In accomplishing these and other objects of the invention, I have provided the improved details of structure hereinafter described and illustrated in the accompanying drawings, wherein:

Figure I is a perspective view of a window sash equipped with a ventilator constructed according to my invention. Fig. II is an enlarged perspective view of end sections and a central part of the ventilator, showing one of the end sections located within the sash. Fig. III is a perspective view of a part of the outside screen and box, showing the connecting or latch members. Fig. IV is an enlarged perspective view of the inside box, showing the damper frame swung back on its hinge. Fig. V is a cross section of the box. Fig. VI is a detail perspective of the outside box. Fig. VII is a detail perspective of the inside box. Fig. VIII is a detail perspective of the preferred form of inside screen plate. Fig. IX is a perspective view of a modified form of inside plate.

Referring more in detail to the parts:—1 designates the outside box of the ventilator, which is constructed of sheet metal, and has a curved bottom 2 for draining outwardly over the outer face of the sash to which the

ventilator is applied, the box 1 being of proper dimensions to fit within an opening made therefor in a window sash and comprising a keeper-plate 3 which is adapted to bear against the outer face of a sash, around the opening, to retain the box in place. 60 The keeper-plate 3 may be provided with apertures 4, through which screws may be projected to permanently fix the flange to the window sash, and preferably covers about one-half of the upper portion of the 65 box to leave a lower opening 5 for the intake of air, a rib 6 connecting the upper and lower portions of the keeper-plate to strengthen same at about its central point, and the lower portion 2 of the box being extended 70 over the lower rail of the keeper-plate so that water will drain outside of the outer face of the sash.

In the outside box 1 is a longitudinal opening 7, which may be of any desired width, 75 but preferably extends throughout the upper half of the box, so that air entering through the outer keeper-plate must travel a tortuous path as it enters the ventilator, the material at the lower edge of the opening 80 being preferably turned outwardly and downwardly to form a dust stop 1'. The opening 7 is broken by a central rib 8, having a key slot 9, with the curved enlargements 10 at its middle portion for receiving 85 the key 11 of a screen 12. The screen is of slightly greater width and length than the opening 7, and adapted to overlie the latter, so that air entering the ventilator must pass therethrough and be screened or ventilated 90 during its passage, the screen being removable, but adapted for adjustment to the outer box by means of the key 11, which comprises a shank that turns in the screen plate and carries a lip member 13 which is adapted 95 for projection through the key slot 9, and for turning back of the rib 8 to hold the plate to the box. The key has a handle portion 14 projected into the opening in the sash, and by which the key may be turned 100 and the screen held when the inner parts are exposed by removal or adjustment of the entire damper frame, as will presently be described. Fitting within the sash opening at the inside of the sash is a box 15 having 105 flanges 17 turned over the face of the sash and fixed thereto by screws or the like 18.

In the base of the box is a longitudinal

opening 19 which preferably occupies almost the entire area of the box, and in the flanges 20 at the end of the opening are key slots 21 corresponding to the slots 9 in the outside box, except that they are two in number and located at the ends of the opening instead of in a rib at the center. Removably applied to the base of the box, and covering said opening, is a plate 22, having a key 23 at each end, corresponding with the key 11 just described, and adapted for similar use in co-operation with the slotted base of the box 16, so that the plate may be fixed to or removed from the box at will.

15 It is my intention to provide the ventilator with two screen plates 22, one to have a longitudinal opening in its lower portion so that air passing through the ventilator will be deflected or retarded and the other having a large opening occupying practically the entire area of the plate and adapted to pass a greater amount of air therethrough.

16 Hingedly mounted within the box, in front of the screen plate, is a damper frame 24, the hinge carrying the frame preferably comprising curved flanges 25 which are hung on and adapted for revolution over a rod 26 which is carried by the ends of the box and extends across the lower portion thereof. The frame 24 has an upper flange 27 adapted for projection into the box opening at the top, and has keys 28 adapted to turn into slots 29 in the ends of the box 16 when the frame is closed. The frame 24 has damper openings 30 formed by spaced ribs 31, and in the central rib is a horizontal slot 32 through which the handle stud 33 of a damper plate 34 is slidably projected. 20 The plate 34 is held to the front of the damper frame by the handle stud and rides on the hinge flanges 25 so that it is held closely against the back of the frame and in horizontal alinement, while being free to travel longitudinally and thereby regulate the area of the openings in the plate.

25 Presuming the parts to be constructed and assembled as described, and the opening in the window sash to be of proper dimensions, the outside box is projected into the sash opening from the outer side thereof and fixed permanently to the sash, as illustrated, the curved bottom of the box being projected slightly beyond the outer face of the shaft when the box is in place. The parts of the front box are assembled as shown and the box inserted into the sash opening from the inner side of the window and also fixed permanently to the sash.

30 When the ventilator is in use, air entering the lower part of the outer box is deflected upwardly by the curved bottom and around the dust stop, to pass to the screened opening in the outer box through which it passes 35 into the chamber formed between the outer

and inner boxes, the dust stop arresting any dust or solid matter which might be carried in the air and pressing the current of air to help in obviating draft. After entering the sash chamber the air passes the upper part 70 of the screen plate and is deflected downwardly to the screen, passing through the screen and thence through the damper frame, in this way being screened twice during its irregular passage through the ventilator.

35 When it is desired to clean the ventilator, the damper frame is unlocked from the box and swung downwardly on its hinge to expose the inside screen. The inside screen 80 may then be removed by turning the keys 23 to register with the key slots and then lifting the screen out through the opening made by the removal of the damper frame. The outside screen may then be removed by 85 turning the key 11 to registration with the key slot, and lifting the screen away from the back box. An open passage is then left through the sash openings and the screens 90 can be brushed or cleaned before they are put back into their boxes.

40 It is apparent that with a ventilator of this construction, the outside box is protected so that rain, snow or dust can not enter the inside of the ventilator, and so that 95 water will drain out away from the box and onto the window sill. It is also apparent that not only is the ventilator adapted to prevent the intake of dust, or the like, into a room, but that whatever dust may enter 100 may be easily and quickly removed when the ventilator is taken apart, as described.

Having thus described my invention, what I claim as new therein and desire to secure by Letters-Patent, is:—

45 1. The combination with a window sash having an opening therein, of a box mounted in said opening and comprising an outer portion having a lower opening, and a deflector curved upwardly and inwardly from the lower edge of said opening, and having an outturned edge forming a dust stop.

50 2. The combination with a window sash having an opening therein, of a box located in said opening and comprising spaced inner and outer portions, the outer portion having an opening at the bottom and the inner portion having an opening at the top, and a deflector curved upwardly and inwardly from the bottom of the outer opening, and having an outturned dust stop at the bottom of the inner opening.

55 3. The combination with a window sash having an opening therein, of a box located in said opening and comprising spaced inner and outer portions, the outer portion having an opening at the bottom and the inner portion having an opening at the top, a deflector curved upwardly and inwardly from the bottom of the outer opening, and having an 60

outturned dust stop at the bottom of the inner opening, and a screen removably mounted in the inner opening.

4. The combination with a window sash having an opening therein, of a box mounted in said opening and comprising an outer portion having a lower opening, and an inner portion having an upper opening, a deflector curved upwardly and inwardly from the bottom of the outer opening and

having an outturned edge provided with a depending lip, forming a dust stop at the bottom of the inner opening, and a screen removably mounted in said upper opening.

In testimony whereof I affix my signature 15 in presence of two witnesses.

ISIDOR POMERANTZ.
